UNITED STATES PATENT OFFICE

168,108

DECORATIVE FOLDABLE SCREEN

Oscar Moessner, Union, N. J.

Application May 17, 1952, Serial No. 19,761

Term of patent 3½ years

(Cl. D29—1)

To all whom it may concern:

Be it known that I, Oscar Moessner, a citizen of the United States, and a resident of the city of Union, county of Union, and State of New Jersey, have invented a new, original, and ornamental Design for a Decorative Foldable Screen, of which the following is a specification, reference being had to the accompanying drawings, forming part hereof and in which:

Fig. 1 is a front elevational view of a decorative foldable screen, showing my new design;

Fig. 2 is a top plan view thereof;

Fig. 3 is a front elevational view thereof in a partially folded position;

Fig. 4 is a side elevational view thereof in a partially folded position; and

Fig. 5 is a top plan view thereof in a partially folded position.

I claim:

The ornamental design for a decorative foldable screen, as shown.

OSCAR MOESSNER.
